[57] CLAIM

The ornamental design for a recreational vehicle trailer
leveler, as shown and described.

DESCRIPTION

FIG. 1 is a perspective view of a recreational vehicle
trailer leveler showing our new design;

FIG. 2 is a top plan view thereof;

FIG. 3 is a side elevational view thereof, the opposite
side being a mirror image of the shown;

FIG. 4 is a bottom plan view thereof;

FIG. 5 is a rear elevational view thereof; and,

FIG. 6 is a front elevational view thereof.
